CLAIM

The ornamental design for a combined wrist rest and pad for use with computer mouse, as shown and described.

DESCRIPTION

FIG. 1 is a top plan view of a combined wrist rest and pad for use with computer mouse, showing my new design;

FIG. 2 is a front elevational view thereof;

FIG. 3 is a left side elevational view thereof, the right side elevational view being the mirror image thereof;

FIG. 4 is a rear elevational view thereof; and,

FIG. 5 is a bottom plan view thereof.

FIG. 1

FIG. 2

FIG. 3

FIG. 4

FIG. 5
